UNITED STATES PATENT OFFICE

JOHN E. BELL, OF BROOKLYN, NEW YORK; LOLA R. BELL EXECUTRIX OF SAID JOHN E. BELL, DECEASED

WASTE-HEAT BOILER

Application filed October 1, 1923. Serial No. 665,762.

My present invention relates to waste heat boilers for utilizing the available heat in hot gases heavily laden with dust discharged from industrial furnaces, and was primarily devised, and is especially adapted for use in a plant in which the boiler heating gases are those issuing from rotary cement kilns. The general object of my invention is to provide an improved arrangement of the heating gas flues and passages whereby the problems due to the presence of cement or other furnace dust in heating gases are solved in a novel and satisfactory manner. My invention is characterized by the introduction of the heating gases into the boilers at the tops of the latter, and is further characterized by a special arrangement of boiler heating surface proper and superheating surface of a superheater boiler whereby certain advantages are obtained as hereinafter explained.

The various features of novelty which characterize my invention are pointed out with particularity in the claims annexed to and forming a part of this specification. For a better understanding of the invention, however, its advantages and specific objects attained with its use, reference should be had to the accompanying drawings in which I have illustrated a preferred embodiment of my invention.

Of the drawings:

Fig. 1 is a diagrammatic plan view of a portion of a cement kiln plant including waste heat boilers; and

Fig. 2 is a section on the line 2—2 of Fig. 1.

In the drawings, I have illustrated the use of my invention in a waste heat boiler system for utilizing the hot gases from a battery of rotary cement kilns A each of which normally discharges its hot gases into a common bus flue D. In accordance with the usual practice seats or guideways C are provided for damper or valve arrangements for closing each of the connections D' from the various kilns A to the flue D when necessary, and a stack B is provided for each kiln A being connected thereto only when the corresponding connection D is closed. Associated with the flue D are one or more, and in practice usually the latter, waste heat boil-

ers F, each boiler being connected to the flue D by an individual flue connection E having provisions, including damper guideways or seats E², by which the boiler may be disconnected from the flue D when this is necessary or desirable. Each boiler F has an outlet for the spent heating gases which is connected to suitable draft creating means shown as comprising an individual exhaust fan G and stack H for each boiler. In so far as above described the apparatus illustrated is of a conventional type well known and in general use.

Each of the flue connections E by which heating gases are passed to the boiler F is arranged, in accordance with the present invention, to pass the heating gases into the top of the corresponding boiler housing. As shown, the boilers are located alongside the flue D with the top of each boiler housing at a level but little above that of the top of the flue, and each flue connection E comprises an uprising portion leading away from the flue D, a horizontal portion in which the damper guideway E² is formed, and a down-comer portion E' opening to a heating gas inlet F² in the top wall of the boiler housing. While some of the advantages of the invention are obtainable with various types of boilers, I prefer to employ a boiler of the horizontal water tube, cross drum type illustrated. The boiler shown comprises two generally similar banks I and I' of water tubes slightly inclined to the horizontal. The water tubes in each of the banks I and I' are connected to the usual headers I², and each upper header is connected to the subadjacent header by nipples I³. Above the lower header of the top bank of tubes I is located a steam and water drum I⁴, which is connected to the upper end of the top front header by horizontal circulating tubes I⁵, which are immediately beneath the flat top wall F' of the boiler housing in which the heating gas inlet F² is formed at the side or end of the boiler remote from the steam and water drum I⁴. Two baffles J and J' divide the inter-tube space of the boiler into three transverse passes for the heating gases. The final pass communicates at its lower end with the outlet flue F³.

running to the corresponding exhaust fan G, and a dust pocket F⁴ is formed in the boiler setting to receive the dust settling out of the gases in passing through the first and second passes of the boiler. Suitable provisions illustrated in part, but which it is not necessary to describe herein, are provided for removing dust collecting in the pocket F⁴.

Advantageously a superheater K is placed 10 at the boiler heating gas inlet F² in front of the first pass of the boiler proper. As shown the superheater K² is composed of U shaped tubular elements, the legs of which are substantially horizontal and are connected to the 15 superheater inlet and outlet headers K' and K² respectively. These headers are advantageously located immediately above the top of the upper header I² of the top bank of tubes I, so that the superheater tube elements 20 may be cleaned and replaced when this becomes necessary, through a normally closed doorway E³ in the wall of the flue portion E' located immediately above the flat top wall F' of the boiler housing. The wall F' then 25 forms a platform for workmen engaged in replacing the superheater tube elements, or removing dust accumulations and incrustations from the superheater, as by means of steam lances or pokers. The accessibility of 30 the superheater for cleaning and tube replacement just referred to, constitutes one of the practically important characteristics of the invention.

In passing dust laden heating gases down 35 into a tube bank there is a tendency for the dust accumulation to be heaviest at the top of the bank where the heating gases first contact with the tubes and with the present invention this initial large dust deposit occurs 40 in the superheater where its removal is most readily effected. The location of the superheater immediately in front of the first pass of the boiler proper, insures the desired amount of superheat with the minimum 45 amount of superheater surface, and the cooling of the heating gases due to their passage through the superheater K is especially important in the construction illustrated, because the horizontal circulating tubes I⁵ are 50 not normally filled with water but normally contain both steam and water, and hence are more apt to be injured by overheating than are the water filled tubes of the boiler. With the described arrangement the superheater 55 forms a protecting gas cooling mantle or screen for the circulating tubes I⁵. Since the flow of the heating gases through the first pass of the boiler is downward, gravity assists in carrying the dust in the heating 60 gases entering the boiler proper, through the inter-tube space of the first pass of the boiler to the top of the dust pocket F⁴ into which this dust largely settles because of the reduced velocity of heating gas flow consequent upon its reduction in temperature and 65

volume as it travels through the first pass, and the reversal in direction of gas flow as the heating gases pass from the first pass to the second pass. The dust settling out of the gases passing upward through the second 70 boiler pass also collects in the dust pocket F⁴, and in practice the great bulk of the dust settling out of the heating gases in the boiler setting is received in the boiler pocket F⁴ where it does not interfere with the operation of the boiler and with which provisions for removing the dust may readily be associated. 75

The initial introduction of the heating gases into the boiler at the top facilitates a 80 proper water circulation through the water tubes and headers which is a matter especially important because of the relatively great number of tube rows and vertical depth of the intertube space which is desirably employed 85 in a waste heat boiler. With the type of boiler illustrated the major portion of the heat absorbed by the boiler is absorbed in the upper portion of the boiler, indeed more than half of the total amount of heat taken up by the 90 boiler will ordinarily be absorbed in the portions of the tubes I in the first pass of the boiler. In consequence the circulation of steam and water in the boiler proper is much more rapid in the upper bank of tubes I, the 95 headers I² connected thereto and connections from those headers to the steam drum I⁴, than in the lower portion of the boiler. With the 100 most rapid boiler circulation thus localized in the upper portion of the boiler, the minimum frictional impedance to the required circulation is secured. In the type of boiler 105 illustrated, the circulation in the lower bank of tubes I' will be to a considerable extent, a local circulation upward through the lowermost tubes I' into the corresponding upper header I², and thence back through the uppermost tubes I' into the lower header I² to 110 which the tubes I' are connected, and the flow through the nipples I³ may be commensurate 115 with the rate at which water is actually evaporated in the bank of tubes I'. 120

While in accordance with the provisions of the statutes I have illustrated and described the best embodiment of my invention now known to me it will be apparent to those skilled in the art that changes may be made in the form of the apparatus disclosed without departing from the spirit of my invention as set forth in the appended claims, and that in some cases certain features of my invention may sometimes be used to advantage without a corresponding use of other features. 125

Having now described my invention, what I claim as new and desire to obtain by Letters Patent, is:

1. The combination in a waste heat boiler of the horizontal water tube type transversely baffled to provide a plurality of transverse passes for the heating gases, of means provid- 130

ing an inlet for the heating gases opening downward to the upper end of the transverse pass adjacent one end of the boiler, and common means for collecting dust separating out of the heating gases in said pass and the pass immediately adjacent thereto.

2. The combination with a waste heat boiler having a bank of horizontally inclined water tubes, and a heating gas inlet at the top of said boiler, of a superheater comprising horizontal tubes located in and extending across a vertical passage connected to said heating gas inlet and above said water tubes.

3. The combination with a waste boiler and its housing, of a heating gas inlet flue opening downward into the boiler through the top wall of the boiler housing, and formed with a lateral doorway accessible from said top wall, and a superheater located in said flue and accessible for cleaning and tube replacement through said doorway.

4. The combination with a waste heat boiler of the horizontal water tube cross drum type having horizontal circulation tubes above a bank of inclined water tubes, and having a heating gas inlet at the top of the boiler and above said circulation tubes, of a superheater above said inlet and said circulation tubes, and means for passing the heating gases into the boiler through said superheater and downward past said circulation tubes.

5. A waste heat boiler comprising upper and lower banks of water tubes slightly inclined to the horizontal, separate headers for each bank of tubes, nipples connecting the adjacent headers of the two banks, a steam and water drum, horizontal circulation tubes connecting said drum to the upper header of the upper tube bank, and means for passing the boiler heating gases through the upper bank of tubes before bringing them into contact with the tubes in the lower bank whereby a relatively slow steam and water circulation is had in the lower bank of tubes and in said nipples.

6. A waste heat boiler of the horizontal water tube type transversely baffled to provide three passes for the heating gases and provided with a heating gas inlet at the upper end of the pass adjacent one end of the boiler, a dust collecting pocket beneath the last mentioned pass and the adjacent pass, and a heating gas outlet communicating with the lower end of the remaining pass.

55 Signed at 111 Broadway, N. Y., in the county of New York and State of New York this twenty-eighth day of September, A. D. 1923.

JOHN E. BELL.
